SUBMARINE FOUNDATION AND METHOD OF
ERECTING

William A. Hunsucker, Los Angeles, Calif.

Application December 18, 1948, Serial No. 66,026

17 Claims. (Cl. 61—46)

1

The present invention relates in general to supporting structures or foundations and, more particularly, the invention relates to a foundation adapted to be erected on and anchored in the earth beneath a body of water and to a method of constructing or erecting a foundation on such a site.

As a matter of convenience, the adjective "submarine" will be employed hereinafter as descriptive of a foundation erected on such a site, i. e., on the surface of the earth beneath a body of water, with the understanding that the invention is not limited in application to a structure for erection in the sea, but may also be applied to structures for erection in fresh water. However, the invention has particular utility when applied to a foundation for erection in the sea in coastal regions to support a derrick and other equipment for off-shore drilling of oil wells, and will be considered in this connection hereinafter for purposes of illustration.

Various types of submarine foundations for use in off-shore drilling operations have been employed heretofore, wooden and metallic foundations being typical examples. Wooden foundations, usually comprising large numbers of piles driven into the earth at the desired site, are subject to several disadvantages, one of these being that the piles are subject to attack by marine borers. Another disadvantage of such wooden foundations is that the load distribution to the piles is indeterminate so that a very rigid superstructure is required to insure that a number of piles sufficient to support the load applied to the foundation are engaged. A further disadvantage of such wooden foundations is that very heavy equipment for driving the piles is necessary, particularly where the water depth exceeds fifty feet, so that the erection of such foundations is quite expensive.

Metallic foundations, even if only partially prefabricated and assembled on the desired site, are quite expensive because of the heavy equipment, e. g., barges, hoists, and the like, required to transport and place the components thereof, particularly where the water depth exceeds fifty feet or so. At water depths of one hundred feet, conventional wooden and metallic foundations become almost impractical because of prohibitive erection costs. Another disadvantage of metallic foundations is, of course, that they are subject to corrosion, which is particularly severe in sea water, unless all of the components thereof are corrosion resistant, or thoroughly waterproofed. Still another disadvantage of metallic founda-

2

tions which are assembled on the site is that divers must be used extensively in assembling the components thereof.

A primary object of my invention, therefore, is to provide a submarine foundation and a method of erecting it which obviate the foregoing and various other disadvantages of submarine foundations employed heretofore.

More specifically, a primary object of the invention is to provide a submarine foundation whose principal load-supporting components are not subject to attack by corrosion, marine borers, or the like and to provide a submarine foundation which may be erected with relatively light equipment and relatively inexpensively even in very deep water, i. e., even in water of a depth of one hundred feet or more.

Another object of the invention is to provide a submarine foundation which is extremely rigid, particularly insofar as vertical loads are concerned.

Still another object is to provide a submarine foundation which includes relatively few load-supporting members to insure determinability of load distribution.

A further object is to provide a submarine foundation which may be erected on the desired site in a relatively short time.

Still another object is to provide a submarine foundation which includes relatively few submerged members to minimize the lateral forces applied to the foundation by wave action. Preferably, the effect of currents or wave action is further minimized by making all of the submerged members of circular cross section, which is still another object of the invention.

Still another object is to provide a method of erecting a submarine foundation by assembling its components on the desired site and which minimizes the use of divers.

An important object of the present invention is to provide a method of erecting a submarine foundation which involves erecting a relatively light initial structure which is supported only by the surface of the earth beneath the body of water covering the desired site and which is capable of supporting the equipment necessary for completing the foundation.

More specifically, an object of the invention is to provide a method which involves erecting an initial structure comprising a plurality of tubular columns supported by the surface of the earth under the body of water covering the site and interconnected by braces to provide a framework

for supporting the equipment necessary to complete the submarine foundation.

Another object is to provide such an initial structure in which the tubular columns are supported by a template resting on the surface of the earth at the site.

An important object is to provide a template having guide means for locating the tubular columns. A related object is to provide a guide means which includes a plurality of guides respectively adapted to receive the lower ends of the tubular columns, and to provide cooperating elements on the template and on the tubular columns for transmitting the weight of the tubular columns to the template so that the latter supports the columns.

Still another object is to provide guides comprising openings through the template so that the lower ends of the columns may be inserted therethrough into the earth predetermined distances to stabilize the initial structure.

An important object of the invention is to provide an initial structure wherein the main braces interconnecting the tubular columns are tensionable and are provided with means for tensioning them at points above the surface of the body of water to minimize the necessity for employing divers in assembling the initial structure.

An important object is to provide a method of converting the initial structure into a durable and substantial submarine foundation through the use of equipment supported by the initial structure.

More specifically, an object of the invention is to provide a method of converting the initial structure into a durable and substantial submarine foundation which involves forming columns of cementitious material, such as concrete, within the tubular columns and extending downwardly therebeneath substantial distances into the earth.

Another object of the invention is to provide a method which involves displacing earthen material from beneath the tubular columns upwardly therethrough, as by drilling, for example, to produce shafts which extend downwardly from and register with the lower ends of the tubular columns, and which involves filling such shafts and at least the lower ends of the tubular columns with cementitious material which is adapted to set to produce cementitious columns extending upwardly from the lower ends of the shafts into the tubular columns.

Another object of the invention is to provide a submarine foundation of the foregoing character wherein the cementitious columns contain reinforcing elements of a material such as steel, for example, and wherein the reinforcing elements are substantially completely enclosed by cementitious material to prevent corrosion thereof by the surrounding water.

Another object of the invention is to provide a method of preventing caving in of the earthen material surrounding the shafts as the latter are formed. More specifically, an object of the invention is to provide a method which involves inserting tubular casings through the tubular columns and into the shafts as the shafts are formed so as to prevent cave-ins. Such tubular casings need be employed only if the earthen material is of such a nature that it tends to cave in readily.

Another object is to withdraw the tubular casings, if used, from the shafts and from the tubu-

lar columns as the latter are filled with cementitious material so that the tubular casings may be used in the erection of other subsequent submarine foundations, whereby to minimize expense.

The foregoing objects and advantages of the present invention, together with various other objects and advantages thereof which will become evident, may be attained through the utilization of the exemplary embodiments of the invention which are illustrated in the accompanying drawings and which are described in detail hereinafter. Referring to the drawings:

Fig. 1 is an elevational view of a partially completed submarine foundation of the invention and illustrates one step of the method of the invention;

Fig. 2 is a horizontal sectional view taken along the broken line 2—2 of Fig. 1;

Fig. 3 is a fragmentary, perspective view on an enlarged scale illustrating a portion of an initial structure of the submarine foundation;

Fig. 4 is an enlarged, fragmentary, elevational view of another portion of the initial structure;

Fig. 5 is a sectional view taken along the broken line 5—5 of Fig. 4;

Fig. 6 is an enlarged, fragmentary, elevational view illustrating one embodiment of still another portion of the initial structure;

Fig. 7 is a sectional view taken along the broken line 7—7 of Fig. 6;

Fig. 8 is an enlarged, fragmentary, elevational view of a reinforcing structure for use in a cementitious column forming part of the submarine foundation;

Fig. 9 is a sectional view taken along the broken line 9—9 of Fig. 8; and,

Figs. 10 and 11 are enlarged sectional views taken along the broken lines 10—10 and 11—11, respectively, of Fig. 1 of the drawings.

Referring particularly to Fig. 1 of the drawings, the numeral 20 designates a submarine foundation for supporting any desired structure, such as a derrick 21 and associated equipment (not shown) for drilling an oil well, or the like. The submarine foundation 20 is erected on a surface 22 of the earth beneath a body of water 23 and is anchored in the earth, the surface of the body of water being designated by the numeral 24.

As a matter of convenience, the structure of the submarine foundation 20 will be discussed in terms of the method of assembling the components thereof.

The first step in the erection of the submarine foundation 20 involves erecting an initial structure, indicated generally by the numeral 27, which rests on the earth surface 22 and which is adapted to support equipment for converting the initial structure into the completed submarine foundation, as will be discussed hereinafter. The initial structure 27 includes a column support or template 28 which is placed on the earth surface 22. For example, the template 28 may be placed on the earth surface 22 by lowering it through the body of water 23 from a barge (not shown), or the like, from the water surface 24. In the particular construction illustrated, the template 28, as best shown in Fig. 2 of the drawings, is of rectangular configuration, although any desired configuration may be employed without departing from the spirit of the invention.

The template 28 includes a frame 29 which includes diagonal braces 30 at its corners to provide triangular spaces 31. Supporting panels 32 of wood or other suitable material may be dis-

posed in the triangular spaces 31 and suitably secured to the template frame 29 to increase the bearing area. The panels 32 are provided to support the initial structure 27 and the herein-after discussed equipment for converting the initial structure into the submarine foundation 20. The size of the panels 32 will depend on the load per unit area which the earth surface 22 is capable of supporting. For example, if the earth surface 22 is capable of supporting large loads per unit area, the panels 32 may be relatively small or may be eliminated. On the other hand, if the earth surface is soft and is capable of supporting only small loads per unit area, the panels 32 may be made sufficiently large to include the entire area, or substantially the entire area, of the template frame 29.

The template 28 includes guides 35 for receiving the lower ends of tubular columns 36, the latter preferably being of circular cross section to minimize the lateral forces applied thereto by wave action in the body of water 23. The tubular columns 36 perform a dual function as follows: (1) during the existence of the initial structure they act as columns capable of supporting moderately heavy loads, (2) they act as form members to contain the cementitious material during the transition from the initial to the final structure. As a matter of convenience the words "tubular column" will be used hereinafter to denote a generally vertically tubular column and form member.

In the particular construction illustrated, the guides 35 are four in number and comprise openings through the template 28 at the four corners thereof, the openings being defined by rings 37. However, the number of guides 35, as well as the configuration of the template 28, may be varied as desired. The tubular columns 36, which are of sufficient length to extend above the water surface 24, may be inserted into the guides 35 from a barge (not shown), or the like, with or without the assistance of a diver, depending upon the depth and clarity of the water and upon the skill of the operator of the hoist (not shown) or other equipment used. Connected to each tubular column 36 adjacent the lower end thereof are two main braces 38 which are of sufficient length to extend above the water surface 24 when inclined at acute angles with respect to the tubular column to which they are connected, as shown in Fig. 1 of the drawings. The main braces 38 are connected to the tubular column 36 adjacent the lower ends thereof before inserting the lower ends of the tubular column into the guides 35 so that the main braces may be employed to control the tubular column from above the water surface 24 as the lower ends of the columns are inserted into the guides, which is a feature of the invention.

In order to stabilize the initial structure 27 against lateral forces which may result from wave action, currents or contact by boats, the tubular columns 36 are inserted into the earth predetermined distances below the surface 22 thereof, as illustrated in Fig. 1 of the drawings. Insertion of the tubular columns 36 into the earth is limited by elements 39 on the tubular columns adjacent the lower ends thereof, the elements 39 being adapted to engage the rings 37 defining the guides 35 and thus serving as stops for limiting insertion of the columns into the earth. In the particular construction illustrated, the elements 39 comprise laterally extending lugs

welded or otherwise secured to the tubular columns 36.

The tubular columns 36 are preferably formed of relatively thin metal, typically about $\frac{3}{8}$ '- $\frac{1}{4}$ ', so that if the earth at the site is relatively hard the tubular columns 36 may be driven the predetermined distances into the earth with relatively light equipment. It will be understood that the thickness range indicated is merely illustrative and may be extended, if desired. On the other hand, if the earth at the site is relatively soft, the weight of the tubular columns may be sufficient to produce the desired penetration.

In Fig. 1 of the drawings, I have shown the tubular columns 36 as vertical, the guides 35 being directed vertically to permit vertical positioning of the columns. However, it will be understood that the invention is not limited to positioning the columns 36 vertically since the columns may be inclined if desired.

After the tubular columns 36 have been placed in the foregoing manner, they are connected to the template 28 and to each other in a manner about to be described. As best shown in Fig. 3 of the drawings, the template frame 29 has pivotally connected thereto adjacent each guide 35 a pair of braces 42 spaced 90° apart. Complementary braces 43 are pivotally connected to each tubular column 36 adjacent the lower end thereof. The braces 42 and 43 are respectively provided with differentially-spaced holes therethrough to receive bolts 44, or the like, the holes in the braces 42 and 43 being so located that small adjustments in brace length can be obtained by placing the bolt 44 in different sets of holes. Preferably, the braces 42 or the braces 43, carry slidable collars 45, each of the latter being slidable into a position such that it encircles the corresponding braces 42 and 43 to secure them together. The collars 45, when so positioned, maintain the braces 42 and 43 in their proper relative positions to facilitate insertion of the bolts 44 through the holes in the braces and to prevent jackknifing of the braces about the bolt axes after the bolts have been inserted in the holes.

The braces 42 and 43 are preferably respectively attached to the template frame 29 and the tubular columns 36 before the template frame and columns are lowered into place so that the braces 42 and 43 may be connected by a diver in the foregoing manner with a minimum expenditure of time and effort. In order to prevent the braces 42 and 43 from obstructing the guides 35 during insertion of the tubular columns 36 therewith, the braces 42 may be swung away from the guides 35 and the braces 43 swung upwardly before lowering the template 28 and the columns 36. Preferably, the pivotal connections between the braces 42 and 43 and the template 28 and columns 36 provide sufficient friction to retain the braces in such positions. Alternatively, the braces 42 and 43 may be lightly secured in such positions, as by means of readily breakable tape (not shown), for example.

As previously suggested, the main braces 38 are connected to the tubular columns 36 before the latter are inserted into the guides 35 so that they may be used to control the tubular columns from above the surface 24 of the body of water 23 as the columns are lowered into place. I prefer to employ flexible cables for the main braces 38, each of the main braces being connected to a suitable bracket 48 adjacent the lower end of the corresponding tubular column 36 by means

of a clevis 49 in the particular construction illustrated. After the tubular columns 36 have been positioned with respect to the template 28 in the foregoing manner, or after at least two of the columns have been positioned, the main braces 38 are connected to adjacent columns at points 50 above the water surface 24 so that such connections may be made by workmen above the water surface, which is a feature of the invention. Since each tubular column 36 has two main diagonal braces 38 connected thereto adjacent its lower end, and spaced 90° apart after all of the connections have been made at the points 50, each column will be connected to two adjacent columns spaced 90° apart. The main diagonal braces may be connected to the column 36 at the points 50 in any suitable manner. For example, each main brace may be connected at its upper end to one of the columns 36 by means of a bracket and clevis corresponding to those discussed previously.

Each main diagonal brace 38 carries an adjusting means, illustrated as a tensioning device, such as a turnbuckle 51, which is also located above the water surface 24. Thus, the main diagonal braces 38 may be tensioned from above the water surface after the necessary connections have been made, which is another feature of the invention.

In order to increase the rigidity of the initial structure 27, I prefer to interconnect the tubular columns 36 by additional horizontal braces 52 located above the water surface 24, there being, in the particular construction illustrated, four such braces each of which is connected at its ends to two of the tubular columns 36 at the points 50 in any suitable manner. For example, the braces 52 may be connected to the columns 36 in the manner illustrated in Figs. 4 and 5 of the drawings and described in more detail hereinafter. The braces 52 are relatively rigid to maintain the desired spacing between the columns 36 and may be formed of a tubular material such as steel, for example.

The tubular columns 36 are further interconnected above the water surface 24 by means of flexible diagonal braces or cables 55 which extend diagonally between the points 50 and points 56 adjacent the upper ends of the columns. The diagonal braces 55 are provided with adjusting means, illustrated as tensioning devices, such as turnbuckles 57, located above the water surface 24. It will be understood that there are two diagonal braces 55 for each of the columns 36, each pair of diagonal braces being spaced 90° apart in the particular construction illustrated.

In the event that the submarine foundation 20 is erected in relatively deep water, e. g., water of a depth of seventy-five feet or more, it is desirable to interconnect the tubular columns 36 intermediate the template 28 and the points 50 so as to eliminate any tendency of the columns to buckle by decreasing the effective column lengths thereof. The tubular columns 36 are shown as interconnected between the template 28 and the points 50 by horizontal braces 60 which may be similar to the horizontal braces 52 described previously. Four braces 60 are employed in the particular construction illustrated, each of these braces being connected at its ends to two of the columns 36 at points 61. As best shown in Figs. 4 and 5 of the drawings, each tubular column 36 is provided with two pairs of ears 62 located at the points 61 and spaced 90° apart. The braces 60 are flat at their ends, as indicated at 63, the flattened ends of the braces being inserted be-

tween the ears of the respective pairs and being suitably secured thereto, as by bolts 64. As previously indicated, the horizontal braces 52 may be secured to the tubular columns 36 at the points 50 in a similar manner. If the horizontal brace 60 is used, auxiliary flexible braces or cables 67 extending diagonally between the points 50 and 61 are also used and may be connected to the tubular columns 36. As is the case with the diagonal braces 55, there are two auxiliary braces 67 spaced 90° apart for each column 36. The auxiliary braces 67 may be connected to the column 36 in substantially the same manner as the main braces 38. The auxiliary braces 67 also carry adjusting means, illustrated as tensioning devices, such as turnbuckles 68, located above the water line 24.

In order to facilitate connecting the horizontal braces 60 to the tubular columns 36, the ends of each brace are initially connected respectively to the auxiliary braces 67 to be lowered into position thereby, the connections of the braces 60 to the columns being easily completed by a diver.

It will be noted that it is necessary to employ a diver for only a relatively small number of operations in erecting the initial structure 27, particularly if the depth of the water is such that the horizontal braces 60 may be eliminated. Thus, the initial structure may be erected substantially entirely from above the water surface 24, which is an important feature of the invention. Also, as will be discussed in more detail hereinafter, the initial structure 27 may be converted into the completed submarine foundation 20 with all operations necessary being performed from above the water line 24, which is another feature of the invention.

The initial structure 27 also includes a superstructure 70 which may be connected to the tubular columns 36 in any suitable manner at any time after the columns have been placed. The superstructure 70 provides a platform for equipment to be used subsequently in converting the initial structure 27 into the completed submarine foundation 20, and also provides a base for the derrick 21 or other structure to be erected on the submarine foundation after it has been completed. Further, the superstructure 70 provides additional rigidity for the initial structure 27 by interconnecting the tubular columns 36 at their upper ends.

It will be noted that the various hereinbefore discussed interconnections between the tubular columns 36 provide for the initial structure 27 a framed structure or framework which makes a pattern of triangles in each face of the structure. This triangular pattern of bracing of the tubular columns 36 results in an initial structure 27 which is relatively rigid and which is capable of supporting relatively large loads. As previously pointed out, the initial structure 27 is supported only by the template 28, which rests on the earth surface 22.

Referring to Figs. 6 and 7 of the drawings, if the components below the water line 24 are not coated by a waterproofing agent and if the horizontal braces 60 are employed, the auxiliary flexible braces 67 may be omitted and an alternate method used of bracing the columns 36 by means of clamping the main diagonal braces 38 to the horizontal brace 60 as shown in Figs. 3, 6 and 7, the braces 60 preferably being so located that each brace 60 and the corresponding pair of main braces 38 intersect at a common point to

permit such clamping. However, if the components below the water line are waterproofed, and particularly if a brittle waterproof coating is employed, it is desirable to eliminate the clamps 71 to prevent cracking the waterproofing.

The foregoing completes the description of the initial structure 27 and the method of its erection and the method of converting the initial structure into the completed submarine foundation 20 will now be considered.

Referring particularly to Fig. 1 of the drawings, after erection of the initial structure 27 has been completed, a portable drilling apparatus 75 of any suitable type is placed on the superstructure 70 and positioned over one of the tubular columns 36. A drill 76 is then lowered through the tubular column into contact with the earth at the lower end thereof, the drill 76 being carried by a drill string 77 which is supported by block-and-tackle means 78 in the particular construction illustrated. The drill string may be rotated by means of a rotary table 79 which is driven by a motor 80, for example.

The drill 76 is operated to produce a shaft extending downwardly from and registering with the lower end of the tubular column 36 over which the portable drilling apparatus is placed, a partially completed shaft being designated by the numeral 83 in Fig. 1 of the drawings. The earthen material removed by the drill in forming the shaft 83 is displaced upwardly through the shaft and the tubular column thereabove. The final depth of the shaft 83 with respect to the earth surface 22 depends on the nature of the earth structure beneath the site and also depends on the weight of the derrick 21 and associated equipment (or other structure) for which the submarine foundation 20 is designed. In other words, if a relatively hard formation capable of withstanding large loads per unit area obtains under the submarine foundation 20 and/or if the load to be supported is relatively small, the shaft 83 may be relatively shallow. On the other hand, if a relatively soft formation capable of supporting only light loads per unit area obtains and/or if large loads are to be applied to the completed submarine foundation 20, a deeper shaft will be necessary. In view of the wide range of earth structures which may be encountered, it is difficult to offer any specific values for the final depth of the shaft 83. However, I contemplate making the final shaft 83 approximately one hundred to two hundred feet deep for average formations and for a shaft and tubular column diameter of the order of magnitude of from two feet to four feet. However, it will be understood that these values are illustrative only.

After the shaft 83 has been drilled to the required depth, the drill 76 is removed therefrom and from the corresponding tubular column 36 and similar shafts are drilled through the remaining tubular columns, a completed shaft being indicated in Fig. 1 of the drawings by the numeral 84. After completed shafts 84 have been provided beneath the respective tubular columns 36, the portable drilling apparatus 75 may be removed from the superstructure 70. It will be understood that the showing of the rotary drill 76 is intended as illustrative only since other equipment may be employed for forming the shafts 84. For example, a drill of the reciprocating type (not shown) may be employed in conjunction with means for bailing loosened earthen material from the shafts through the tubular columns 36. Consequently, it will be understood that I do not de-

sire to be limited to any specific equipment for forming the shafts 84.

In the event that the earth structure at the site is such that cave-ins are likely to occur, I prefer to insert a tubular casing 87 through each tubular column 36 into the partially completed shaft 83 therebeneath as the shaft is formed, the casing closely following the drill 76 to provide a retaining wall for preventing cave-ins. The drill 76 is of a size to pass through the tubular casing 87 so that the drill may be removed from the shaft and the corresponding tubular column without removing the tubular casing. However, as will be discussed in more detail hereinafter, the tubular casing 87, if employed, is preferably removed prior to completion of the submarine foundation 20 to reduce costs and permit the concrete to be cast directly in contact with the walls of the shaft to conform to surface irregularities thereof and form an effective anchor and foundation support.

As each of the shafts 84 is completed, or after any desired number of shafts have been completed, I insert a reinforcing element 88 downwardly thereto through the corresponding tubular column 36, an example of a suitable reinforcing element being illustrated in Figs. 8 and 9 of the drawing. As illustrated therein, the reinforcing element 88 comprises vertical reinforcing rods 89 having a helical reinforcing rod 90 secured thereto in any suitable manner. Spacers 91 are secured to the reinforcing structure 88 and serve to prevent contact of the reinforcing element with the walls of the tubular columns 36 and the shafts 84.

The length of the reinforcing element 88 inserted into each tubular column 36 and shaft 84 is preferably such that the reinforcing element extends from a point adjacent the lower end of a shaft to a point above the lower end of the tubular column. The reinforcing element preferably extends above the water surface 24 and may extend substantially to the top of the tubular column. Preferably, the reinforcing element is so supported that its lower end is spaced upwardly from the lower end of the shaft 84 slightly for a reason which will be pointed out hereinafter.

After the reinforcing element 88 has been inserted into one of the tubular columns 36 and the corresponding shaft 84, the shaft and tubular column are filled with a cementitious material, such as concrete. At this point the tubular column performs the second part of its dual function, i. e., of acting as a form into which the wet, plastic cementitious material is placed. The tubular column 36 and the corresponding shaft 84 may be filled with cementitious materials by means of a tremie pipe, a bottom dump bucket, or other suitable means. Positioning the lower end of the reinforcing element slightly above the lower end of the shaft permits the lower end of the reinforcing element to be completely encased in cementitious material, and spacing the reinforcing element inwardly from the walls of the shaft and the tubular column by means of the spacers 91 permits the entire reinforcing element to be encased by an annular jacket of cementitious material. This prevents water from coming in contact with the reinforcing element after the cementitious material has set so as to prevent corrosion of the reinforcing element, which is a feature of the invention. The tubular column is filled with cementitious material to a point above the upper end of the reinforcing element, which

11

point may be anywhere above the lower end of the tubular column and preferably at the upper end thereof. After the cementitious material has set, there results a continuous reinforced, cementitious column 92 extending from the lower end of the shaft 84 upwardly into the corresponding tubular column 36, and preferably substantially to the upper end thereof so that the superstructure 70 may be connected directly thereto in any suitable manner. The foregoing procedure is repeated for all of the tubular columns 36 and shafts 84, thereby providing four cementitious columns 92 in the particular construction illustrated.

In the event that employment of the tubular casing 87 is necessary to prevent cave-ins in a particular shaft 84, I insert the reinforcing element 88 into the tubular casing. Subsequently, as the cementitious material is poured, I withdraw the tubular casing from the shaft 84 as successive portions of the shaft become filled with cementitious material, the cementitious material serving to prevent cave-ins after the tubular casing has been withdrawn. Thus, the tubular casing 87, or casings if more than one is employed, may be used many times, which is a feature of the invention.

After the reinforced cementitious columns 92 have set, an extremely durable and substantial submarine foundation results and the desired apparatus to be supported thereby may then be mounted on the superstructure 70.

My invention thus provides a durable and substantial submarine foundation 20 which may be erected with relatively light equipment and with relatively little expense, which is the primary object of the invention.

Although I have disclosed various embodiments of the submarine foundation and the method of the invention for purposes of illustration, it will be understood that various changes, modifications and substitutions may be incorporated in such embodiment without necessarily departing from the spirit of the invention and I hereby reserve a right to all such changes, modifications and substitutions.

I claim as my invention:

1. A method of erecting a column extending completely through a body of water and of anchoring said column in the earth beneath said body of water, said method involving the use of a tubular column of sufficient length to extend completely through said body of water, and involving the use of a column support which is adapted to be sustained substantially on the surface of the earth below said body of water by the earth therebelow and which is engageable by said tubular column in an upright position to sustain said tubular column, said method including the steps of: lowering said column support through said body of water onto the surface of the earth therebelow; lowering said tubular column through said body of water into engagement with said column support while in said upright position so that said column support sustains said tubular column, the upper end of the tubular column then being above the surface of said body of water; removing earthen material from beneath said tubular column and while the water is in contact with the exterior thereof, thus providing a shaft which extends downwardly from and registers with the lower end of said tubular column; and filling said shaft and at least a portion of said tubular column above said lower end thereof with a cementitious material adapted to set to produce

12

a cementitious column shaped by the shaft and extending from the shaft into said tubular column.

2. A method as defined in claim 1, involving the additional use of a guide on said column support of a size to receive said tubular column, which method includes the step of guiding the lower end of said tubular column into said guide on said column support while lowering said tubular column through said body of water.

3. A method as defined in claim 2 employing a guide member and including the additional steps of attaching said guide member to said tubular column before lowering said tubular column through said body of water, and pulling on said guide member from a position above the surface of said body of water to guide said lower end of said tubular column into said guide on said column support.

4. A method of erecting a submarine structure to be supported by the earth beneath a body of water, said method employing a plurality of tubular columns each of a length to extend completely through the body of water and a plurality of bracing members, said method including the steps of: lowering said tubular columns through said body of water and spacing the lower ends of said tubular columns in a predetermined configuration; then connecting said bracing members between the tubular columns to form a pattern of triangles in each face of the structure; drilling downwardly into the earth beneath each tubular column to provide a shaft which extends downwardly from and registers with each of said tubular columns; and filling each shaft and at least a portion of its associated tubular column with a cementitious material adapted to set to produce a cementitious column extending from said shaft into the corresponding tubular column.

5. A method of erecting a submarine structure to be supported by the earth beneath a body of water, said method employing a plurality of tubular columns each of a length to extend completely through the body of water, said method employing also a plurality of bracing members, said method including the steps of: attaching at least one bracing member to each of said tubular columns; lowering said tubular columns in said body of water to submerge the point of connection with the bracing member and while retaining the upper end of the bracing member above the surface of the body of water; pulling on said bracing member to move the lower end of each tubular column to a predetermined position and lowering each tubular column to be supported in this position by the earth, thus forming a plurality of spaced tubular columns; and diagonally bracing said tubular columns by extending the bracing member of each tubular column diagonally to an adjacent tubular column and securing same thereto to form a rigid initial structure.

6. A method as defined in claim 5, including the step of drilling downwardly into the earth beneath each tubular column to provide therebeneath a shaft which extends downwardly from and registers with the lower end of such tubular column; and filling each of said shafts and at least a portion of each of the associated tubular columns with a cementitious material adapted to set to produce a cementitious column which extends from each shaft upwardly into its corresponding tubular column.

7. A method of erecting a submarine structure to be supported by the earth beneath a body of water, said method employing a plurality of tubu-

lar columns each of a length to extend completely through the body of water, said method employing also a plurality of bracing members, said method including the steps of: connecting to a lower portion of each tubular column at least one bracing member; lowering said tubular columns into contact with the earth at the bottom of the body of water while guiding each tubular column to engage the earth at a predetermined position by pulling on its bracing member from above the surface of the body of water; and connecting the upper end of each bracing member connected to a tubular column to an adjacent tubular column at a position above the body of water to employ said bracing members as diagonal braces between adjacent tubular columns and provide a rigid initial structure.

8. A method of erecting a column on the surface of the earth and of anchoring said column in the earth, said method involving the use of a tubular column, involving the use of a column support which is adapted to be sustained by the earth substantially on the surface thereof and which is engageable by said tubular column in a generally vertical position to sustain said tubular column, and involving the use of a tubular casing of a size to be received by said tubular column, said method including the steps of: positioning said column support on the surface of the earth; positioning said tubular column generally vertically in engagement with said column support to be sustained thereby; displacing earthen material from beneath said tubular column upwardly therethrough to produce a shaft extending downwardly from and registering with the lower end of said tubular column; inserting said tubular casing downwardly through said tubular column and into said shaft as earthen material is displaced upwardly so as to prevent caving in of the earthen material surrounding said shaft; and filling said shaft and at least a portion of said tubular column above said lower end thereof with cementitious material adapted to set to produce a cementitious column which extends from the lower end of said shaft upwardly into said tubular column.

9. The method set forth in claim 8, including the additional step of withdrawing said tubular casing from said shaft and said tubular column as said shaft and said portion of said tubular column are filled with cementitious material so that the resulting cementitious column contacts the walls of said shaft and said tubular column.

10. A submarine structure extending from the surface of the earth beneath a body of water to a position above the surface of the body of water, said structure forming an open, multi-sided, skeletal framework exposed to currents and wave motion in said body of water, said structure comprising: a template engaging said surface of the earth beneath said body of water and having a substantially vertical guide; a substantially vertical column having a lower end slidably received by said guide and extending downwardly therethrough; stop means for limiting the downward movement of said column through said guide and including means for transmitting to said template the weight of said column and vertical loads imposed thereon; a brace; means for connecting one end of said brace to said column at a position above said guide; and means for operatively connecting the other end of said brace to said template at a position spaced laterally from said guide, said

brace holding said column in a substantially vertical position.

11. A submarine structure extending from the earth beneath a body of water to a position above the surface of the body of water, said submarine structure comprising: a base member resting on the surface of the earth beneath said body of water, said base member providing a plurality of guides; a plurality of tubular column members lowerable through said body of water, each tubular column member extending through said body of water to said surface thereof and each tubular column member providing a lower end receivable by a corresponding guide of said base member, said base member positioning said lower ends of said tubular column members in fixed spaced relationship to form an open skeletal framework; means for guiding the lower end of each tubular column member to be received by its corresponding guide of said base member, said guiding means including a bracing member connected to a lower portion of each tubular column member; and means for diagonally bracing spaced tubular column members of said skeletal framework, said bracing means including means for adjustably connecting the upper end of each bracing member to an upper portion of another tubular column member to extend diagonally across the space between such other tubular column member and the tubular column member to the lower portion of which such bracing member is connected.

12. A submarine structure as defined in claim 11 including an additional relatively short bracing means and means for connecting same between one of said tubular column members and said base member at submerged positions to hold such tubular column member in upright position after its lower end is received by the corresponding guide of said base member.

13. A submarine structure as defined in claim 11 in which said base member underlies the lower end of said open skeletal framework to form a support therefor, and in which said guides are positioned at the corners of said base member whereby the corresponding tubular column members form corners of said open skeletal framework.

14. A submarine structure extending from the earth beneath a body of water to a position above the surface of the body of water, said submarine structure comprising: a base member resting on the surface of the earth beneath said body of water, said base member providing a plurality of guides each having open upper and lower ends; a plurality of tubular column members lowerable through said body of water, each tubular column member extending through said body of water to said surface thereof and each tubular column member providing a lower end slidably received by said guide so that such lower end extends through said guide and into the earth a substantial distance below said guide, said base member positioning said lower ends of said tubular column members in fixed spaced relationship; interengaging means between each tubular column member and its corresponding guide for limiting the movement of such tubular column member through such guide and thus limiting the depth to which the lower end of such tubular column member penetrates the earth beneath said base member, said interengaging means transmitting to said guide and to said base member the weight of such tubular column member;

and a plurality of bracing members extending diagonally between said spaced tubular column members in a pattern of triangles to form an open, multi-sided and skeletal framework presenting a minimum impedance to currents and wave motion in said body of water.

15. A submarine structure supported by the earth beneath a body of water, said structure comprising in combination: a plurality of tubular column members each of a length to extend completely through said body of water with their lower ends penetrating into the earth beneath the body of water; means adjacent the surface of the earth beneath said body of water for spacing said tubular column members a fixed distance from each other and in a predetermined pattern to form an open skeletal framework; a plurality of bracing members between said tubular column members to form substantially a pattern of triangles in each face of said skeletal framework; shafts excavated in the earth downwardly from and registering with each of said tubular column members; and cementitious material filling each shaft and at least a portion of its associated tubular column member to form cementitious columns in said shafts and extending into the corresponding tubular column members, said cementitious material being in direct contact with the walls of said shafts to conform to surface irregularities thereof so as to transmit to the earth adjacent the perimeters of the shafts the weight of said skeletal framework and loads imposed thereon.

16. A submarine structure supported by the earth beneath a body of water, said structure comprising in combination: a massive template supported by the earth beneath said body of water, said template providing a plurality of spaced guides; a plurality of tubular column members each of a length to extend completely through said body of water, said tubular column members being received by said guides and being spaced by said guides to form an open skeletal framework; a plurality of bracing members between the spaced tubular column members to form substantially a pattern of triangles in each face of said skeletal framework; shafts excavated in the earth downwardly from and registering with each of said tubular column members; and cementitious material filling each shaft and at least a portion of its associated tubular column member to form cementitious columns in said shafts and extending into the corresponding tubular column members, said cementitious material being in direct contact with the walls of the shafts to conform to surface irregularities thereof so as to transmit to the earth adjacent

the perimeters of the shafts the weight of said skeletal framework and loads imposed thereon.

17. A submarine structure extending from the earth beneath a body of water to a position above the surface of the body of water, said submarine structure comprising: a base member resting on the surface of the earth beneath said body of water, said base member providing a plurality of guides; a plurality of tubular column members lowerable through said body of water, each tubular column member extending through said body of water to said surface thereof and each tubular column member providing a lower end received by a corresponding guide of said base member, each guide and its corresponding tubular column member providing an interengaging means limiting the lowering movement of such tubular column member relative to such guide and transferring vertical loads from such tubular column member to such guide and to said base member, said base member positioning said lower ends of said tubular column members in fixed spaced relationship to form an open skeletal framework with said base member underlying same and forming a support therefor; means for guiding the lower end of each tubular column member to be received by its corresponding guide of said base member, said guiding means including a bracing member connected to each tubular column member at a position above said interengaging means; and means for diagonally bracing adjacent tubular column members of said skeletal framework, said last-named means including means for adjustably connecting the upper end of each bracing member to an upper portion of another tubular column member to extend diagonally across the space between such other tubular column member and the tubular column member to the lower portion of which such bracing member is connected.
